SWITCH

Herbert E. White, Cleveland Heights, Ohio

Application February 25, 1944, Serial No. 523,929

3 Claims. (Cl. 200—138)

1

My invention pertains to thermostatic switches.

An object of my invention is to provide a new and improved thermostatic switch.

Another object of my invention is to provide a bi-metallic type of thermostatic switch which is sensitive to small changes in temperature.

It is another object of my invention to provide a thermostatic switch which responds rapidly to changes in temperature.

A further object of my invention is to provide a small circularly shaped thermostatic switch.

It is also an object of my invention to provide a thermostatic switch having a plurality of adjustment means for determining the temperature range over which it operates.

An object of my invention is to provide a thermostatic switch for use in a low voltage circuit, and one which may stand unused for long periods of time in a dusty place and still operate.

A detailed object of my invention is to provide a new and improved thermostatic switch for operating a fire alarm from a low-voltage electrical circuit such as a door bell circuit, and which may remain unused for years in a dusty place and still operate efficiently in spite of a dirt film, should the emergency arise.

Other objects and a fuller understanding of my invention may be had by referring to the following description and claims, read in conjunction with the drawings in which:

Figure 1 is a side view of my thermostatic switch.

Figure 2 is a top view of the switch shown in Figure 1.

Figure 3 is a sectional view taken along lines 3—3 of Figure 2.

Figure 4 is a sectional view taken along lines 4—4 of Figure 1, showing the contacts in their open position.

Figure 5 is a sectional view similar to Figure 4, but showing the contacts in their closed position.

Figure 6 is a view of a portion of a modified form of thermostatic switch utilizing adjustable contacts.

My invention comprises an annular base portion 10 preferably formed of some relatively strong insulating material such as "Bakelite" or the like, to which is connected an arcuate metallic electrical conductive portion 11. Screws or hollow rivets 12 (Figure 5) may be utilized for connecting the arcuate conductive portion 11 to the insulating base 10.

A spacer block 13 (Figure 4) is connected to

2

the insulating base 10 by means of hollow rivets 14, and the rivets also connect a circular bimetallic strip 15 to the base portion.

The bi-metallic strip 15 is made up of a first 5 lamination 16 of a material which has a high coefficient of thermal expansion and a second lamination 17 of a material having a lower coefficient of thermal expansion. The two laminations are connected together substantially 10 throughout their entire length as is common practice in bi-metallic strips, and is bent around the insulating base portion 10. The bi-metallic strip 15 has two end portions 18 and 19, to which, respectively, there are connected two electrical 15 contact members 20 and 21. Except for the portion of the bi-metallic strip 15 which is in engagement with the spacer block 13, the entire strip and its contact members 20 and 21 are normally spaced away from the arcuate conductive portion 11 and away from the base portion 10 to allow for radial movement of the bi-metallic strip 15, toward the circular base portion 10 under the influence of a rising temperature until the contact members 20, 21 engage the arcuate 25 conductive portion 11. While this is the preferred form of my invention it is to be understood that in another arrangement, normally the contact members 20, 21 could be in engagement with the arcuate conductive portion 11 and be arranged 30 to move away therefrom under the influence of a rising temperature until the contact between the arcuate conductive portion 11 and the contact members 20, 21 is broken.

A first electrical lead 22 may be connected to 35 the bimetallic strip 15 by means of a screw 23 or the like, and a second electrical lead 24 may be connected to the arcuate electrical conductive portion 11. A hole 31 is provided in the bottom plate 26 through which the lead 24 passes, and 40 a screw 32 connects the lead to the electrical conductive portion 11. A screw 33 is used to connect the lead 22 to the bi-metallic strip 15. By utilizing screws 32, 33 for attaching the leads to the switch may easily be put into an electrical 45 circuit.

When the switch is closed the electrical circuit is from lead 22 through the bi-metallic strip 15 to the contact member 20 which is in contact with the arcuate conductive portion 11 and completing the circuit through the lead 24.

For ease in mounting the switch on walls or on timbers such as are found in basements and for protecting the switch I provide a housing member comprised of a top plate 25 and a bottom plate 26 of insulating material. The two plates

25 and 26 are held together and to the circular base member 10 by means of a hollow rivet 27 or the like which passes through the hollow center of the base member. Within the hollow center of the base member 10 I provide a centering washer 28 having a central hole through which the hollow rivet 27 passes. One of the plates 25, 26 may have an extended portion 29 through which there is a hole 30 by means of which the device may be easily mounted to some external supporting means such as a wall.

Figure 6 illustrates a modification of my device in which the arcuate metallic electrical conductive portion 11 is adjustably mounted on the base portion 10, and in which the contact members 20, 21 are adjustable to vary the temperature setting of the thermostatic switch. It is to be understood that either the conductive portion 11 alone or the contact members 20, 21 alone, or both may be adjustable in a thermostatic switch.

The conductive portion 11 may be adjusted by means of the screws 35 which extend through the conductive portion 11 and which have enlarged end portions 36. Screws 35 threadably engage the base portion 10, and springs 37 are positioned around the screw between the base portion 10 and the conductive portion 11 and tend to expand thereby biasing the conductive portion 11 away from the base 10. When the screws 35 are turned inwardly toward the base 10 the springs 37 thrust the conductive portion 11 toward the bimetallic member 15, and as the screws 35 are withdrawn from the base 10 the springs 37 are squeezed and the conductive portion 11 moves away from the bimetallic member 15.

Each contact member 10 and 21 is adjusted by means of one of the two screws 38 to which it is connected. The screws 38 extend through the bimetallic strip 15 and may be turned in one direction to advance the contact members 20, 21 toward the conductive portion 11, and turned in the other direction to withdraw them away from the conductive portion 11.

The temperature setting for a given thermostatic switch is set by the normal spacing between the contact members 20, 21 and the conductive portion 11. The closer the spacing between the contact members and the conductive portion the smaller the temperature change necessary to close the switch.

My switch may be made either to open or close a circuit upon a rise in temperature, and it may be made to open or close a switch upon a drop in temperature.

One important use for my switch is to operate fire alarms, such as in factories and private homes, and may be made to operate from a low voltage source such as a door bell circuit. In such an installation it is desirable for the switch to normally be open and upon being heated to close a circuit and ring a bell or otherwise operate an alarm device.

It is desirable that the switch operate in spite of a layer of dust and dirt which may gather on the contact members 20, 21 and on the conductive portion 11 when the switch remains in an attic or basement for a long period of time, and it is desirable that the action of the switch be rapid when it is heated.

By utilizing a circular construction as shown I obtain a sliding contact between the contact members 20, 21 and the conductive portion 11 which breaks through any layer of dirt which may be present thereby establishing a good contact, and by utilizing more than one contact

member I increase the chance for good contact under very adverse conditions.

In order to assure rapid action of the switch without resorting to snap-action types which are more expensive and which may become inoperative due to dirt, I position the bi-metallic strip 15 around the base 10 with the portion 16 which has the higher coefficient of thermal expansion on the outside where it more readily receives the heat, and with the portion 17 which has the lower coefficient of thermal expansion on the inside where it is shielded on one side by the portion 17 and on the other side by the central base portion 12. Thus, even the slightest amount of heat is utilized to cause a bending of the bi-metallic strip 15, and if the amount of bending is sufficient the switch will be closed.

While I have described my invention with a certain degree of particularity it is to be understood that numerous changes in the construction and the arrangements of the parts may be made without departing from the spirit and scope of my invention.

I claim as my invention:

1. In a thermostatic switch, a circular base portion, an arcuate electrical conductive portion connected to said base at one side thereof, an arcuate bi-metallic electrical conductive portion connected to said base at the opposite side thereof, said bi-metallic portion being wrapped about base and having two contact portions each of which is positioned in over-lapping relation with a portion of said arcuate electrical conductive portion and each of which is adapted to engage the conductive portion to make an electrical circuit, only two electrical terminal means one of which is electrically connected to said arcuate electrical conductive portion and the other of which is electrically connected to said bi-metallic portion, a top cover and a bottom cover each connected to said base portion and extending outwardly from said circular base around the periphery thereof, said bi-metallic portion being protected on three sides by said base and said two covers, and said bi-metallic portion having its portion with a higher coefficient of thermal expansion positioned to the outside of the portion with the lower coefficient of thermal expansion whereby the portion with the lower coefficient is protected on four sides.

2. In a thermostatic switch, a cylindrical base portion, an arcuate electrical conductive portion connected to said cylindrical base at one side of its outer face, an arcuate bi-metallic electrical conductive portion connected to said cylindrical base at the opposite outer face thereof, said bi-metallic portion being wrapped about said cylindrical base and having two contact portions each of which is positioned in over-lapping relation with a portion of said arcuate electrical conductive portion, only two electrical terminals one of which is electrically connected to said arcuate electrical conductive portion and the other of which is electrically connected to said bi-metallic portion, either of said two contacts of said bi-metallic portion upon engaging said conductive portion establishing an electrical circuit between said two terminals.

3. A thermostatic switch comprising, in combination, a base, an electrical conductor connected to said base, a bi-metal connected to said base and having two contact portions each positioned in overlapping relationship with a portion of said electrical conductor, said bi-metal being in substantially an arc of a first circle and said elec-

trical conductor being in an arc of a second circle having substantially the same center as said first circle and with a slightly different radius so that in operation the said two contact portions slide across said electrical conductor whereby a double wiping contact is made which scrapes away any dirt which may be on the contact portions of said switch, only two electrical terminal means one connected to said electrical conductor and the other connected to said bi-metal, said bi-metal being arranged so that upon a change in temperature in one direction each of said two contact portions moves with respect to said electrical conductor to make a single electrical circuit upon either one of said two contact portions engaging said electrical conductor and upon a

5

change in temperature in the opposite direction to break the circuit upon both of said contact portions disengaging from said electrical conductor.
